[57] CLAIM

The ornamental design for an electric tractor vehicle, as shown and described.

DESCRIPTION

FIG. 1 is a top, front and left side perspective view of an electric tractor vehicle showing my new design;

FIG. 2 is a front elevational view thereof;

FIG. 3 is a side elevational view thereof from the left of FIG. 2, the side opposite that shown in FIG. 3 being the mirror image thereof;

FIG. 4 is a rear elevational view thereof;

FIG. 5 is a top plan view thereof;

FIG. 6 is a bottom plan view thereof; and,

FIG. 7 is a side elevational view thereof on a reduced scale and with an attached vehicle shown in broken lines for illustrative purposes only and forming no part of the claimed design.

FIG. 2

FIG. 3

FIG. 4

FIG. 5

FIG. 6

FIG. 7
